Application filed March 23, 1887. Serial No. 232,199. Term of patent 7 years.

To all whom it may concern:

Be it known that I, HENRY M. BETZ, a citizen of the United States, residing in Philadelphia, Pennsylvania, have invented a new and original Design for a Badge, of which the following is a specification.

My design for a badge, medal, or seal is fully illustrated in the accompanying drawings, in which—

10 Figure 1 is a face view of a medal, and Fig. 2 is a side view of the same.

My design comprises a central representation of a safe, and around this is a scalloped ring, and beneath the safe is the representa-

tion of a ribbon with its ends forked and turned over.

I claim—

The design for a badge, substantially as described, and as shown in and by the accompanying drawings.

20 In testimony whereof I have signed my name to this specification in the presence of two subscribing witnesses.
